UNITED STATES PATENT OFFICE.

MAX LEVINE, OF NEW YORK, N. Y.

DESIGN FOR A TRAY.

Application filed September 18, 1923. Serial No. 7,259. Term of patent 7 years.

To all whom it may concern:

Be it known that I, MAX LEVINE, a citizen of Russia, residing in the city of New York, borough of Manhattan, county and State of New York, have invented a new, original, and ornamental Design for Trays, of which the following is a specification, reference being had to the accompanying drawing, forming part thereof.

Figure 1 is a plan view of a tray embodying my new design;

Figure 2 is an end view thereof.

I claim:

The ornamental design for a tray as shown.

MAX LEVINE.
